His Attorney.

UNITED STATES PATENT OFFICE

163,565

CLOCKCASE

Leo I. Bruce, Framingham Center, Mass., assignor
to Telechron, Inc., a corporation of Massachu-
sets

Application April 10, 1950, Serial No. 9,095

Term of patent 14 years

(Cl. D42—7)

To all whom it may concern:

Be it known that I, Leo I. Bruce, a citizen of the United States, residing at Framingham Center, State of Massachusetts, have invented a new, original, and ornamental Design for a Clockcase, of which the following is a specification, reference being had to the accompanying drawing, forming a part thereof.

Fig. 1 is a front perspective view of a clockcase showing my new design, Fig. 2 is a side view in diagrammatic outline thereof, and Fig. 3 is a top plan view also in diagrammatic outline.

I claim:
The ornamental design for a clockcase, as shown.

LEO I. BRUCE.
